UNITED STATES PATENT OFFICE.

CARL A. BRINK, OF CRANSTON, RHODE ISLAND, ASSIGNOR TO UNIVERSAL WINDING COMPANY, OF BOSTON, MASSACHUSETTS, A CORPORATION OF MASSACHUSETTS.

WINDING MACHINE.

Application filed October 30, 1922. Serial No. 597,979.

To all whom it may concern:

Be it known that I, CARL A. BRINK, a citizen of the United States, residing at Cranston, in the county of Providence, State of Rhode Island, have invented certain new and useful Improvements in Winding Machines, of which the following is a specification.

This invention relates to winding machines and consists of improvements in the means for controlling the operation of the same.

The principal object of the improvement is to provide a more convenient method of starting and stopping the winding operation whereby the operator is relieved from reaching for the controls and saved from other motions so that the piecing up of ends may be accomplished with less effort and more expeditiously to increase the rate of production of the machine.

More specifically, one object of the improvement is to provide a foot-control for withdrawing the cop or package from contact with its drive-roll, or for otherwise disconnecting it from the driving-means, so that the operator's hands are left free for tying up the yarns or otherwise preparing the machine for winding.

Another particular object of the improvement is to provide for connecting the cop or package with the drive, for instance by replacing it in contact with its drive-roll, through manipulation of the foot-control so that the winding operation may be started more promptly after the piecing up of the yarns.

Further objects of the improvement are set forth in the following specification which describes a preferred embodiment of the invention as illustrated in the accompanying drawings. In the drawings:

Fig. 1 is a cross-sectional elevation of a winding frame having a plurality of winding units mounted thereon, showing one form of the improved foot-control as applied thereto;

Fig. 2, an enlarged cross-sectional view of one of the winding-heads or units showing a portion of the controlling-mechanism therefor;

Fig. 3, a plan view of the cop-supporting frame of the winding-head, showing the

stopping-mechanism which controls the contact of the cop with its drive-roll;

Fig. 4, a cross-sectional view of the frame and its co-related elements taken on the line 4-4 of Fig. 3 looking in the direction indicated by the arrow x, and showing the stopping-mechanism of the machine more in detail;

Fig. 5, a similar view showing the stopping-mechanism in different relation with respect to the operative parts of the machine; and

Fig. 6, a detailed view of the trip-device for the stopping-mechanism and also illustrating the arrangement of the thread-bail for releasing the thread from the traverse-guide.

The present improvements are herein described and illustrated as applied to use in connection with a friction- or drum-driven type of winding machine in which the cop is rotated from surface contact with the periphery of a drum or drive-roll; but it is to be understood that the invention is not limited in this respect as it may be adapted for other types of winders having a positive drive for the package.

Referring to Fig. 1 of the present drawings the winding machine comprises, in general, a table or bed 2 supported from suitable legs or standards 3 and mounting a double row of winding-heads or units H which are embodied in box-like frames 4. There may be any convenient number of winding-heads H spaced at intervals along the bed 2, but in Fig. 1 only two of the opposite units are illustrated. Each unit

comprises, essentially, a constantly driven friction-drum or drive-roll 5; a pivoted frame 6 for rotatably supporting the spindle or mandrel T on which the cop is wound, to adapt the latter to be held with its surface in contact with the periphery of the drive-roll 5; a helical cam 9, also continuously driven; and a thread-guide 10 connected to be reciprocated from the cam longitudinally of the winding-mandrel to deposit the yarn in cross-wound coils thereon.

The above-named elements are common to practically all types of drum-winders and the driving-connections for operating the winding-mechanism are not herein shown or described in detail as they may be of any

well known arrangement such, for instance, as disclosed in U. S. Letters Patent No. 1,326,088, granted to E. F. Parks December 23, 1919.

5 The cop-supporting frame 6, shown in plan view in Fig. 3, is constructed in the form of a yoke having two parallel side-arms 14 and 15 connected by braces or cross-struts 16 and 17. The arms 14 and 15 are 10 bored laterally at 18 to receive a horizontal shaft or rod 19 which serves as a pivot for the frame 6, the rod 19 being supported from overhanging arms 20 on the frame 4, as shown in Figs. 1 and 2. The outer ends of 15 the arms 14 and 15 carry means for rotatably supporting the cop-tube or mandrel T on which the yarn or thread is wound, the tube consisting usually of a cylindrical billet of wood provided with an axial bore t. For 20 this purpose the arm 14 is provided with a bearing 21 in which is journaled a live-spindle 22 having a reduced end 23 adapted to enter the end of the bore t in the tube T. The spindle 22 carries a disk 24 provided with spurs 25 which engage a cross-slot s on the end of the tube T to key the latter rotatively with the spindle. At the outer end of the opposite arm 15 is a similar 25 live-spindle 26 journaled in a bearing at the extremity of a lever 27. The lever 27 is pivoted at 28 to the side of the arm 15 so that it may be swung laterally in relation thereto to release the spindle 26 from the tube T, a spring 29 tending to normally 30 maintain the spindle in place in the bore t of the tube.

Referring to Figs. 1 and 2, the frame 6 supports the mandrel or cop-tube T in position above the drive-roll 5 with the periphery of the tube in contact with the surface of the roll so that it will be rotated therefrom to wind on the yarn. As the yarn is built up on the tube T and the cop increases in diameter the frame 6 will swing upwardly 40 on its pivot 19. The movement of the tube T away from the drive-roll 5 is controlled by suitable dogging-means which acts to prevent the return of the tube toward the roll after it has receded therefrom during the 45 normal growth in the winding. The dogging-means is constructed and arranged as later described.

Pivoted on a stud 30 which projects from 55 the side of the arm 14 of the frame 6 is a lever 31 having a curved arm 32 arched above the bearing 21. At the extremity of the arm 32 is a finger-piece 33 arranged opposite a finger-rest 34 projecting from the end of the arm 14. A spring 35 has its end 60 hooked through a hole in the arm 32 of the lever 31 and is anchored at the opposite end to a lug 36 rising from the top of the arm 14. The spring 35 tends to rock the lever 31 in the direction indicated by the arrow b, Fig. 65 2, and the finger-piece 33 and rest 34 may be

grasped by the operator to rock the lever in the opposite direction for a purpose as later explained. During the normal operation of the machine the lever 31 is maintained in the position illustrated in Fig. 2 by means of a detent-rod 37 which holds it against the force of the spring 35. The rod 37 slides in a bearing 38 on the side of the arm 14 and is beveled off or pointed at its forward end to adapt it to engage a substantially V-shaped notch 39 at the end of a short arm 40 on the lever 31. Below the notch 39 the arm 40 terminates in a wedge-shaped toe 47, while above the notch the end of the arm is of arcuate shape to provide an eccentric 75 cam-face 51 which serves a purpose as later explained.

The opposite, inner end of the detent-rod 37 is bent at right-angles and hooked through a hole 41 in a sickle-shaped lever 42. 85 The lever 42 is pivoted on a stud 43 held in a lug 44 rising from the rearward cross-strut 16 of the frame 6, and is controlled by a spring 45 anchored to the end of a curved lever 46 to be later described. The spring 45 tends to rock the lever 42 to urge the rod 37 into engagement with the notch 39 in the arm 40 of the lever 31. The sickle lever 42 depends from its pivot-pin 43 at the front 90 of the rod 19 on which the frame 6 is hinged and reaches back in under said rod in the curved portion 48 which terminates in a downwardly-extending straight arm 49. Threaded through the end of the arm 49 is a "sizing" screw 50 having a rounded end 100 adapted to bear against the rearward side of the frame 4 on which the winding mechanism is mounted, see Fig. 2. The sizing-screw 50 may be adjusted in the arm 49 of the lever 42 so that its end will contact with the frame 4 when the cop-supporting frame 6 has been rocked upwardly to a predetermined extent by the increase in diameter of the winding. That is to say, the arrangement is such that when the package has 110 reached a predetermined diameter the frame 6 will have been swung upwardly to such an extent that the screw 50 will be brought into contact with the frame 4 to rock the lever 42 in the direction indicated by the arrow c in Fig. 2. The rocking of the lever 42 in this manner will cause it to slide the detent-rod 37 to the left, as viewed in Fig. 2, 115 to withdraw its pointed end from the notch 39 in the lever 31. The lever 31 will thereupon be released, whereupon it will be rocked under the tension of its spring 35 to cause it to actuate certain mechanism, to be later described, which operates to lift the frame 6 to carry the cop or package away 120 from contact with its drive-roll 5.

The detent-rod 37 is also adapted to be released from devices rendered operative upon breakage of the yarn feeding to the cop. Referring to Fig. 1, the yarn y draws up 130

from a supply-cop or bobbin B which is supported from a rod 53 held in brackets on the side of the legs or standards 3, and feeds through a tension-device 54 which may be 5 of any suitable arrangement as usually employed in the art. As shown in Figs. 1 and 2, the tension-device comprises opposite, pivoted grids 55 having fingers across which the yarn draws in a sinuous path; it being 10 understood that when the machine is equipped for winding in multiple a plurality of the tensions are employed, one for each strand to be wound into the cop. Only one of the tension-devices is herein illustrated, 15 however, and the yarn leads upwardly therefrom to the guiding-slot in the reciprocable thread-guide 10 by which it is traversed on the cop C. Intermediate the tension-device and the thread-guide 10 is a wire breakage-lever 60 which is provided with opposite, 20 parallel legs pivoted on a rod 61 extending between a pair of plates 62 projecting forwardly from the frame 4, see Fig. 2. The yarn y draws across a horizontal bar 63, 25 which connects the upper ends of the legs of the breakage-lever 60, and normally maintains the lever in substantially erect position as illustrated in Fig. 2. The lever 60 has a right-angled extension 65 at the lower end of 30 one of its legs which is inserted through a loop 66 at the forward end of a wire link 67. The opposite end of the link 67 is hooked into a hole 68 on the elbow-shaped arm 69 of a pawl-lever 70. The pawl-lever 70 is 35 pivoted on a pin 71 projecting through the sides of a push-bar 72 which is connected at its rearward end to the sickle-shaped lever 42 for operating the detent-rod 37 previously described. As shown in Fig. 2, the curved 40 portion 48 of the lever 42 is provided on its side with an arcuate slot 74 which is engaged by a pin or roller 75 carried at the rearward end of the push-bar 72. The forward end of the push-bar 72 is supported 45 from a rockable arm 77 having a pivotal connection with the bar at 78. The arm 77 is pivoted on a horizontal rod 79 extending between the sides of the frame 4, which rod also serves as a guiding-track for the reciprocable traverse-slide 80 carrying the thread-guide 10; it being noted that said traverse-slide is provided with ears 81 at its upper 50 end which slide on a second cross-rod 82. The arm 69 of the pawl 70 is connected 55 below the pin 71 to an opposite arm 85 formed with a toe 86 adapted to be rocked into position to engage with the rounded teeth 87 on the interior of the rim of a stopping-wheel 88, see Figs. 5 and 6. The 60 wheel 88 is keyed to the shaft 89 which drives the traverse-cam 9, see Fig. 2, and rotates continuously therewith during the operation of the machine. The pawl 70 and its arm 85 are rocked from the link 67 through the connection of the latter with the breakage-lever 65

60 which is adapted to swing to the right, as shown in Fig. 6, when released by the breaking of the yarn y drawing across its horizontal cross-bar 63. A finger 90 projecting from the arm 69 of the pawl 70 is adapted to 70 contact with the top of the push-bar 72 to limit the rocking movement of the pawl. Referring to Fig. 5, one of the legs of the breakage-lever 60 is formed with a U-shaped bend or crook 92 which is adapted to make 75 contact with the end of a lug 93 projecting from the upper end of the arm 77 which supports the outer end of the push-bar 72. When the push-bar 72 has been carried into the position illustrated in Fig. 5, through 80 the operation of the stopping-mechanism as later explained, the arm 77 is rocked to depress its lug 93 to engage it with the crook 92 on the breakage-lever 60. This action causes the breakage-lever 60 to be rocked into 85 vertical position and held there until the winding operation is started again; it being observed that the engagement of the extension 65 on the leg of the breakage-lever 60 with the loop 66 on the link 67 permits a 90 slight movement of the lever without rocking the pawl 70.

The arm 77 also has a further function in operating the thread-bail 95 which lifts the 95 yarn away from the thread-guide 10 upon the arresting of the winding operation. Referring to Fig. 2, the thread-bail or yarn-lifter 95 consists of a narrow plate extending across the front of the machine in close association with the traverse-guide 10. The 100 forward edge of the lifter 95 is rolled over at 96 to adapt it to receive a suitable hinge-rod 97 pivotally mounted in ears 98 which project upwardly from a front cover-plate 100 extending between the sides of the frame 4. On the under side of the lifter-plate 95 is 105 an ear 101 provided with a hole for receiving the hooked end 102 of a rod 103. Referring to Fig. 5, the lower end of the rod 103 is connected to a hooked extension 104 110 by means of a turnbuckle 105 which is employed for adjusting the length of the two-part rod. The hook 106 on the extension 104 is hooked through a hole in the end of a finger 107 projecting from the side of the 115 arm 77. When the arm 77 is rocked into the position illustrated in Fig. 5, during the action of the stopping-mechanism of the machine, the connecting-rod 103—104 will be pushed upwardly to raise the forward end 120 of the thread-lifter 95 to lift the yarn y out of the slot in the traverse-guide 10 in the manner and for the purpose as later explained.

The means operated from the stopping-mechanism to raise the cop from contact with the drive-roll and constituting a part of the improved foot-control will now be described in detail. Referring particularly to Figs. 4 and 5, the arm 40 of the lever 31, 130

which is pivoted on the frame 6, is formed with an abutment 110 on its side providing a bearing for a right-angled rod 111 inserted through a hole 112 at its end. One arm of 5 the rod 111 projects downwardly from the bearing in the form of a pawl 114 which is provided at its end with a sharpened toe 115 adapted to engage with the ratchet teeth 116 of an arcuate rack or quadrant 117. The 10 quadrant 117 has a fixed relation to the frame 6 and, as herein shown, is constructed as a part of the machine frame 4. The rod 111 for the pawl 114 is held in its bearing in the arm 40 of the lever 31 by means of a 15 cotter-pin 118 inserted through a hole in its end. A spring 120 is hooked through the lower, looped end of the pin 118 and anchored at its opposite end to a web 121 projecting from the side of a finger 122 on the 20 lever 31. The spring 120 acts to rock the pawl 114 to carry its toe 115 toward the teeth 116 on the quadrant 117 and the upper end of the pin 118 is adapted to contact with a pin 123 driven into the side of the arm 25 40 to limit the rocking movement of the pawl. The engagement of the pin 118 with the stop-pin 123 acts to hold the pawl 114 normally just clear of the teeth 116 on the quadrant 117. It will be obvious from the 30 above description that when the detent rod 37 is released from the lever 31 and said lever rocked under the force of its spring 35, as shown in Fig. 5, the pawl 114 will first be carried into engagement with the 35 teeth 116 to then operate with a toggle-action to raise the frame 6 to lift the cop off from its drive roll in the manner as more fully explained hereinafter. It is also to be noted that the downwardly extending finger 122 40 on the lever 31 is formed with a lug or abutment 125, shown in dotted lines in Fig. 5, which is adapted to strike against a projection 126 on the frame 6 to limit the rocking 45 action of the lever 31.

It has been explained that during the winding of the cop the frame 6 is swung upwardly as the package grows in diameter, and to control this movement of the cop-carrying frame it has been found expedient 50 to employ a dogging-means as next described: Referring to Fig. 4, the dogging-means consists in an elbow-shaped arm 130 provided with a bearing-rod or shaft 131 pivotally mounted in an arm or extension 55 132 on the under side of the cross-strut 17 of the frame 6. The arm or dog 130 is beveled off on its sides at 135 to provide a wedge-shaped section which engages with a tapered or V-shaped groove 136 cut into the 60 side of the quadrant 117. The lever 46, previously referred to, has its hub secured to the bearing rod 131 of the dog 130 by means of a set-screw 137, and it will thus be seen that the spring 45 which connects the lever 65 46 with the lever 42 will act to normally

maintain the dog 130 in frictional engagement with the groove 136 in the quadrant 117. The arrangement of this part of the mechanism, that is the wedge-shaped dog and grooved quadrant, is well known in the 70 art. Referring now to Fig. 4, the controlling-lever 46 for the dog 130 is provided with a forwardly-extending arm 140 having its end beveled off to form an inclined face 141 which is adapted to be engaged by the 75 lower rounded end of the finger 122 on the lever 31. Through this arrangement the finger 122 is caused to rock the lever 46 to release the dog 130 from the quadrant 117 when the lever 31 is depressed at its forward 80 end, either manually or through the action of the foot-control as later explained.

The means for operating the stopping-lever 31 and its related mechanism from the foot-control is arranged as next described: Referring to Figs. 3, 4 and 5, on the cross-strut 17 of the frame 6 is a bearing 142 in which is pivotally mounted a rod 143 formed with a right-angled arm 145 at one end. Hooked into a hole at the outer end of the arm 145 is a link 146 which is pivotally connected at its opposite end to the arm 40 of the lever 31. On the opposite end of the rod 143 from the arm 145 is a lever 150 secured fast thereto by a binder-screw 151. The lever 150 is provided with two holes 152 and 153, either one of which is adapted to receive the hooked end of a wire rod or link 154. Referring now to Fig. 1, the lower end of the link 154 is hooked into the upper end of a rod 155 which reaches down to a foot-lever or treadle 156. In the present type of machine shown in Fig. 1 an individual foot-lever is provided for each single unit or winding-head on the frame 2 and the levers for opposite units project outwardly from a central horizontal shaft 157 on which the series of levers are pivoted. The shaft 157 is held in bearings on the legs or standards 3 which support the frame 2 at its opposite ends. Each foot-lever or treadle 156 is provided on its side with a projecting rib or plate 159 formed with a series of holes 160 into which the lower end of the rod 155 may be hooked. By adjusting the rod 155 in the different holes in the rib 159 the height of the treadle may be varied in accordance with requirements of its operation.

Having now described the structure and arrangement of the essential parts of the machine its method of operation will next be explained: Fig. 2 of the drawings illustrates the parts of the winder in the position they assume substantially at the start of the winding operation. The winding mandrel or cop-tube T is shown as having a slight amount of yarn wound on its exterior, the first layers of the package C whose surface is held in contact with the periphery of the drive-roll 5 under the weight of the pivoted sup-

porting-frame 6. As illustrated in Fig. 1, the yarn *y* leads up from the supply-bobbin B through the tension device 54, thence across the upper bar 63 of the breakage-lever 60, and through the eye or notch in the traverse-guide 10 to the package C. The package or cop C is rotated through its surface contact with the continuously driven drive-roll 5 and the continuously reciprocating traverse-guide 10 traverses the yarn *y* back and forth to deposit it in helical coils which form the layers of the cop. As the winding increases in diameter with each added layer of yarn the frame 6 is swung gradually upward and the dogging-device 130 acts frictionally on the quadrant 117 to prevent retrogressive movement of the frame whereby to eliminate vibration or jumping of the package on the drive-roll.

It has been explained that during the normal operation of the machine the breakage-lever 60 is maintained in erect position by the traveling yarn *y* leading across its upper bar 63. When the yarn *y* breaks or becomes exhausted at its source of supply, however, the lever 60 will be released and, acting under the force of gravity, will tilt forward into the position shown at the right in Fig. 1. As illustrated more in detail in Fig. 6, this forward rocking movement of the lever 60 causes its projection 65 to be swung back in the direction indicated by the arrow *e* to act through the link 67 to rock the pawl-lever 70, whereby to raise its toe 86 into position to be engaged by one of the teeth 87 on the stop-wheel 88. The wheel 88 is continuously rotated in the direction indicated by the arrow *f* in Figs. 2 and 6, and as the stop-finger 90 on the pawl-lever 70 is brought down against the top of the push-bar 72 the dogging of the pawl on the rim of the wheel will act to slide the push-bar rearwardly or in the direction indicated by the arrow *g* in Fig. 6. As before noted, the opposite end of the push-bar 72 is connected to the detent-lever 42 by means of its roller 75 which rides in the arcuate slot 74 in the arm 48 of said lever as the frame 6 swings upwardly. It will therefore be seen that in whatever position the frame 6 may be the rearward movement of the bar 72 will cause the lever 42 to be rocked in the direction indicated by the arrow *c* in Fig. 2. This movement of the lever 42 acts to slide the detent-rod 37, which is connected therewith, to release its end from the notch 39 in the arm 40 of the lever 31. Upon the release of the lever 31 in this manner its spring 35 will cause it to be rocked in the direction indicated by the arrow *b* in Fig. 2 until the abutment 125 on its finger 122 brings up against the projection 126 on the under side of the arm 14 of the frame 6, see Fig. 5. As the arm 40 of the lever is rocked downwardly it carries the pawl 114 into en-

gagement with the teeth 116 on the quadrant 117 and operates with a toggle action to lift the frame 6, whereby the surface of the cop C is raised away from the periphery of the drive-roll 5, as shown in Fig. 5.

The withdrawal of the cop from contact with the drive-roll serves to arrest its rotation and meanwhile the yarn *y* is raised out from the slot in the thread-guide 10 by the thread-lifter 95. This latter action is effected by the raising of the rod 103—104 under the rocking motion of the arm 77 which is connected to the push-bar 72 and moved therefrom in the manner as later explained. Through the above-described sequence of operations the winding is arrested and the cop held in raised position above the drive-roll until the operator pieces up the yarn.

It will be observed by reference to Fig. 5 that as the arm 40 of the lever 31 is rocked downwardly the end of the detent-rod 37 will ride out on its curved cam-face 51. The cam-face 51 being eccentric to the pivot 30 of the lever 31 causes the rod 37 to be slid farther back against the pressure of its spring 45 to rock the lever 42 to such an extent that it will draw the push-bar 72 rearwardly to remove the pawl-lever 70 from proximity with the rim of the stop-wheel 88. In this manner the toe 86 on the pawl-lever 70 is withdrawn from engagement with the teeth 87 on the wheel to prevent chattering or jumping of the pawl as the wheel continues to rotate. The rearward movement of the push-bar 72 also serves to rock the arm 77 into the position illustrated in Fig. 5 to raise the thread-lifter 95 as before explained and also to depress the lug 93 on the arm into engagement with the crook 92 on the breakage-lever 60 to return the latter to erect position.

In preparing the machine for operation the operator employs both hands for piecing up the ends and with the present improved arrangement of the controlling-means no hand motions are required for starting the machine. The loose end on the cop is drawn off and pieced to the end from the supply bobbin and the free length of yarn held across the hand in order that it may feed properly into the machine without snarling or tangling. As soon as the ends of the yarn are tied or spliced the operator presses with the foot on the treadle 156 and this action returns the parts of the machine to operative position again to continue the winding of the cop in the manner as next explained:

As the foot-lever 156 is depressed it acts through the rods 155 and 154 to rock the lever 150 downwardly whereby the rod 143 is turned to raise its crank-arm 145, as shown in Fig. 4. The arm 145 acts through the link 146 to raise the arm 40 of the lever 31

6
to release the pawl 114 from the teeth on the quadrant 117, and the continued raising of the arm 40 also serves to release the dog 130 from the quadrant. This latter action is effected by the engagement of the lower rounded end of the finger 122 with the beveled face 141 of the arm 140 on the lever 46 which rocks the latter against the force of the spring 45. As soon as the pawl 114 and dog 130 have been released from the quadrant 117 in this manner the pressure of the foot on the treadle 156 is released slightly and the frame 6 is thus allowed to drop slowly under the action of gravity to permit the cop C to be brought gently into contact with the periphery of the drive-roll 5.

It will be noted by reference to Fig. 4 of the drawings that as the lever 150 is swung downwardly by the action of the depressing of the treadle 156 it strikes against the rearward cross-bar 16 of the frame 6 so that the downward movement of the frame is maintained under the control of the operator's foot pressure. It is to be further observed that the full movement of the lever 150 serves to rock the connected lever 31 farther than necessary to engage the detent-rod 37 with the notch 39 in the arm 40. That is to say, as the arm 40 of the lever 31 is rocked upwardly its toe 47 comes against the pointed end of the detent-rod 37 and holds the latter in position to prevent the lever 42 from being swung forward under the force of its spring 45. With the lever 42 held in this relation the push-bar 72 will be maintained in position with the pawl-lever 70 removed away from proximity to the rim of the stop-wheel 88 so that the pawl-arm 85 will not make contact with the teeth 87 on the rim of the wheel to cause chattering or jumping as the wheel rotates. Furthermore, the bar 72 when in this position as illustrated in Fig. 5 serves to hold the lever 77 with its lug 93 rocked downwardly in engagement with the crook 92 on the breakage-lever 60, as before explained. The breakage-lever 60 is thus held in erect position until the yarn can be released from the operator's hand and allowed to draw across its bar 63. Through this arrangement the breakage-lever 60 is prevented from dropping to stop the winding operation as long as the operator's foot is held on the treadle so that the starting of the machine is accomplished without danger of premature stopping before the yarn is replaced in contact with the breakage-lever. After the operator has observed that the machine is operating properly the foot is removed from the treadle 156 and the lever 150 is then allowed to rock back to neutral position with the notch 39 in its arm 40 engaged by the detent-rod 37, as shown in Fig. 2. The parts of the stopping-mechanism will thus be re-

turned to and maintained in inoperative relation ready to become active again upon the breakage of the yarn.

It will be observed by reference to Fig. 5 that when the winding is arrested the winding-mandrel T is raised above the drive-roll 5 to a sufficient extent to give free access to the whole surface of the cop C so that the operator may readily discover and pick up the broken end of the yarn. Should it be required to lift the cop still farther this may be accomplished by pressing on the treadle 156 to draw the lever 150 down against the cross-strut 16 of the frame 6, see Fig. 4, when the lever 150 will act to rock the frame 6 upwardly on its pivot 19. It will thus be seen that with the connecting rod 154 engaged with the hole 153 at the end of the lever 150 the foot-lever or treadle 156 may be employed to either raise the cop from or lower it into contact with the drive-roll. In this way the winding machine is rendered completely under the control of the foot-lever so that the operator's hands are left entirely free for other duties. In some cases where it may not be desired to lift the cop from the drive-roll under foot-control the rod 154 is hooked into the hole 152 in the lever 150. With this latter arrangement the lever 150 will be operated from the treadle 156 in the same manner as previously explained to release the pawl 114, and continued pressure on the treadle will draw the frame 6 downwardly to effect a more prompt return of the cop into driving contact with the roll 5.

It will be evident from the foregoing that the present improvement provides a much more convenient and expeditious method of controlling the operation of the winding machine than the usual hand-control. With the present foot-control both of the operator's hands are left free to piece up broken ends so that the winding operation may be started the instant the splicing is completed without waiting to reach for a hand-lever. Furthermore, the operator is not required to reach in across the cop to grasp the starting lever and this is a most important improvement from a practical standpoint. Usually the operator breaks or cuts off the waste ends of yarn left extending from the knot and holds them in the fingers while starting the machine. With the usual arrangement of starting-mechanism it is necessary to reach above the cop to grasp the starting lever and it has been found in practice that the bits of yarn in the operator's fingers will often be caught up and drawn into the package. If not discovered and removed these loose ends in the cop will be drawn into the twister, doubler or other machine to which the package ultimately delivers its supply and the product of such machine will show faults from the loose ends corkscrewing or

bunching with the other strands. In other cases the waste yarn will be caught in the going parts of the machine where it is liable to cause improper functioning of the mechanism and damage to its parts.

With the present improved arrangement of the controls the operator is not required to reach or otherwise exert himself in starting the machine; hence an erect position may be maintained which greatly reduces fatigue and lessens the labor of the operator whereby greater productivity is accomplished. Furthermore, the product is improved and the capacity of the machine increased due to shorter periods of stopping.

While I have herein shown and described a preferred construction of my improved control-device as applied to a certain type of machine it is obvious that modifications in structure and arrangement and different methods of adapting it for use may be made which would fall within the spirit and scope of the present invention. Therefore, without limitation in this respect, I claim:

1. In a winding machine, the combination with a rotatable winding-mandrel and reciprocable traverse-guide, of driving-means for rotating the mandrel and reciprocating the guide, means to disconnect the mandrel from its driving-means, and a foot-control movable in the same direction for operating said disconnecting-means to either start or stop the winding-operation.

2. In a winding-machine, the combination of a winding-mandrel for supporting the cop being wound, a drive-roll for rotating the cop by surface contact therewith, means for shifting the cop toward and away from the drive-roll, and a foot-control for operating the cop-shifting means, said foot-control movable in the same direction to shift the cop either toward or away from the drive-roll.

3. In a winding machine, the combination with a friction drive-roll, of a movable support for maintaining the cop in contact with the drive-roll, and a foot-control operable under pressure to move the support to carry the cop away from the drive-roll and also operable in the same direction to return the cop into contact with the drive-roll.

4. In a winding machine, the combination with a winding-mandrel, of driving-means for rotating the mandrel to wind the yarn thereon, automatically-actuated stopping-means for rendering the driving-means inoperative upon the breakage of the yarn being wound, a foot-control for resetting the stopping-means to render the driving-means operative again, and means operated from the foot-control to restrain the stopping-means from action until the yarn is returned to controlling position with relation to the stopping-means.

5. In a winding-machine, the combination

with a rotating drive-roll and a reciprocating traverse-guide, of means for supporting the cop in contact with the drive-roll, stopping-means for removing the cop from contact with the drive-roll, means operated from the stopping-means to release the yarn from the traverse-guide, and a foot-control for replacing the cop in contact with the drive-roll and concurrently operating the yarn-releasing means to allow the yarn to be reengaged by the guide.

6. In a winding machine, the combination with a rotating drive-roll and a reciprocating traverse-guide, of means for supporting the cop in contact with the drive-roll, stopping-means for removing the cop from contact with the drive-roll, means for concurrently disengaging the yarn from the traverse-guide, a foot-control for replacing the cop in contact with the drive-roll, and means operated upon the replacement of the cop to release the yarn to adapt it to be reengaged by the traverse-guide.

7. In a winding machine, the combination with a rotating drive-roll, of a frame for supporting the cop in contact with the drive-roll, toggle-means adapted to act on the frame to withdraw the cop from contact with the drive-roll, a detent for maintaining said toggle-means normally inactive, stopping-means for releasing the detent, and a foot-control for resetting the toggle-means and engaging it with its detent.

8. In a winding machine, the combination with a rotating drive-roll, of a frame for supporting the cop in contact with the drive-roll, a lever pivoted on the frame, a pawl carried by the lever, a ratchet, means for operating the lever to engage the pawl with the ratchet to move the frame to withdraw the cop from contact with the drive-roll, and means to operate the lever to release the pawl to adapt the cop to be replaced in contact with the drive-roll.

9. In a winding machine, the combination with a rotating drive-roll, of a frame for supporting the cop in contact with the drive-roll, a lever pivoted to said frame, a pawl carried by said lever, a ratchet, a spring for operating the lever to engage the pawl with the ratchet to move the frame to withdraw the cop from contact with the drive-roll, and a foot-control for moving the lever to release the pawl to adapt the frame to replace the cop in contact with the drive-roll.

10. In a winding machine, the combination with a rotating drive-roll, of a frame for supporting the cop in contact with the drive-roll, a lever pivoted to the frame, a pawl carried by the lever, a ratchet, a spring for operating the lever to engage the pawl with the ratchet to move the frame to withdraw the cop from contact with the drive-

roll, a detent for engaging the lever to render the latter normally inactive, yarn-controlled means for releasing the detent, and a foot-control for moving the lever to release the pawl from the ratchet and effect engagement of the detent with the lever.

11. In a winding machine, the combination with a rotating drive-roll, of a frame for supporting the cop in contact with the drive-roll, a stopping-lever, means to operate the stopping-lever, means operated from the stopping-lever to move the frame to withdraw the cop from contact with the drive-roll, a detent for locking the stopping-lever from operation, knock-off devices for releasing the detent, yarn-controlled means for rendering the knock-off devices operative, and means for holding the knock-off devices inoperative until said detent is locked with the stopping-lever.

12. In a winding machine, the combination with a rotating drive-roll, of a frame for supporting the cop in contact with the drive-roll, as stopping-lever for moving the frame to withdraw the cop from contact with the drive-roll, detent-means for maintaining said stopping-lever normally inactive, a breakage-lever engaged by the yarn and adapted to act when released to disengage the detent-means, and means to hold the breakage-lever inoperative until the stop-

ping-lever is returned to normal position and the detent-means engaged therewith.

13. In a winding machine, the combination with a rotating drive-roll, of means for supporting the cop in contact with the drive-roll, stopping-means for withdrawing the cop from contact with the drive-roll, a breakage-lever for initiating the action of the stopping-means upon the breaking or exhaustion of the yarn, a foot-control for releasing the stopping-means to replace the cop in contact with the drive-roll, and means for preventing premature action of the breakage-lever before the foot-control is released.

14. In a winding machine, the combination with a rotating drive-roll, of means for supporting the cop in contact with the drive-roll, stopping-means for withdrawing the cop from contact with the drive-roll, means for initiating the action of the stopping-means upon the breaking or exhaustion of the yarn, a foot-control for releasing the stopping-means to permit the cop to be replaced in contact with the drive-roll, and means operated by continued pressure on the foot-control to prevent the premature operation of the stopping-means.

In testimony whereof I affix my signature.

CARL A. BRINK.
